UNITED STATES PATENT OFFICE.

DAVID S. YOUNCE, JOSEPH C. SHELLABARGER, AND WILLIAM H. NICHOLAS,
OF WEST MILTON, OHIO.

MACHINE FOR STRINGING TOBACCO UPON LATHS.

SPECIFICATION forming part of Letters Patent No. 364,621, dated June 7, 1887.

Application filed March 19, 1887. Serial No. 231,557. (No model.)

To all whom it may concern:

Be it known that we, DAVID S. YOUNCE, JOSEPH C. SHELLABARGER, and WILLIAM H. NICHOLAS, of West Milton, in the county of 5 Miami and State of Ohio, have invented certain new and useful Improvements in Machines for Stringing Tobacco upon Laths; and we do hereby declare the following to be a full, clear, and exact description of the invention, such as will enable others skilled in the art to which it pertains to make and use it, reference being had to the accompanying drawings, which form part of this specification.

Our invention relates to an improvement in 15 machines for stringing tobacco upon laths; and it consists in the combination of a stationary frame, a sliding table placed thereon and provided with guides to hold the tobacco-plants in position, the spudder, the spring-actuated 20 guides between which it is held, and the holder for the outer end of the lath upon which the plants are being strung, as will be more fully described hereinafter.

The object of our invention is to produce a 25 machine by means of which tobacco-plants can be strung upon laths more quickly and readily than can be done by hand.

Figure 1 is a side elevation of a machine embodying our invention. Fig. 2 is an end 30 view. Fig. 3 is a plan view. Fig. 4 is a perspective of the spudder. Fig. 5 is a detail view of the spudder and the guides. Fig. 6 is a vertical section of the catch which supports one end of the lath. Fig. 7 is an enlarged view of the guides, showing the groove 35 in which the spudder moves.

A represents a stationary frame, and B the sliding table, which is placed thereon, and which moves back and forth in relation to the 40 spudder. This table will be of any suitable construction, and upon which the tobacco-plants are placed preparatory to being strung upon the lath. Suitable friction-rollers are placed under the corners of this table, so as to 45 cause it to slide back and forth more readily than it otherwise would do. Rising from the top of this table, near its inner edge, are the vertical guides C, in between which the stalks of the plants are placed and held, so that they 50 cannot get out of position while being operated upon by the spudder.

Secured to the side of the frame, and extending transversely across, is the beam D, to the outer end of which is secured the vertical upright E. Secured to opposite ends of this upright E are the two arms F, which are connected together by the spiral spring G, so as to be always drawn inward toward each other. To the inner end of each of these arms F is secured a vertical rod, H, to the inner end of which is secured a guide, I. Both of the rods H pass through guides, so as to always retain them in position and cause them to move in a direct line with each other. As the two arms are drawn forcibly toward each other at their free ends by means of the spring G, the two guides are always held forced tightly against opposite sides of the spudder J, which is held stationary in suitable grooves, L, made in the inner side of the guides C. One of these 70 guides, I, is provided with a small projection, which catches in a corresponding recess in the spudder, and thus holds the spudder in position while the table is being forced endwise, so as to force the point of the spudder through 75 the plants as they lie upon the table. In the rear end of the spudder is formed a suitable recess, in which one end of the lath N is made to catch, and the other end of the lath is held in position by the slotted spring-actuated catch 80 O, which is adjustable back and forth upon the upright P, for the purpose of accommodating the length of the lath. The catch O has a series of notches made in its under side, so that they will catch upon the flange which is made 85 upon the end of the support Q. The outer end of the lath catches in a recess made in the inner end of the catch, as shown. The pressure of the spring a applied to the upper end of the upright P keeps the catch forced down upon 90 the flange, and thus prevents it from moving or getting out of position.

The tobacco-plants are laid across the table so that their ends will catch between the uprights or guides C. The guides I, between 95 which the spudder is held, are beveled, as shown, so as to catch under and on top of the ends of the plants and guide them directly toward the spudder as the table is moved backward. This spudder, being sharp-pointed, 100 passes through the stems, and as one plant after the other is impaled upon the spudder

they are forced back upon the lath. As each stem is forced backward through the guides I they automatically move outward to let them pass, and then snap back into position again. 5 As soon as one lath is filled with tobacco it is removed and replaced by another. By means of the construction here shown the plants can be placed upon the lath, ready to be hung up and dried, much more rapidly and quickly 10 than can be done by hand.

Having thus described our invention, we claim—

1. The combination of the stationary frame, the endwise-moving table placed thereon, the 15 uprights or guides C, rising from the table, and between which the ends of the plants are placed, the spring-actuated guides I, the spudder, and a support for holding the outer end of the lath in position, substantially as shown.
2. The combination of the frame A, the endwise-sliding table B, provided with vertical guides C near one edge, the spudder which moves horizontally between the guides, the spring-actuated guides for directing the plants 25 to the end of the spudder, one of them being provided with a small projection to catch in the corresponding recess in the spudder, the lath upon which the tobacco is strung, and the adjustable support for the outer end of the 30 lath, substantially as described.

3. The combination of the support Q, provided with a flange, the notched adjustable catch O, placed upon the spudder, the upright P, which passes through the slot in the catch, and the spring which forces the catch down upon 35 the support, with the lath N, the spudder which supports the other end of the lath, the guides C, the table B, and the spring-actuated guides, substantially as described.

4. The combination of the frame, the end- 40 wise-moving table provided with uprights or guides for holding the plants in position, the cross-beam D, the upright E, connected thereto, the two arms F, connected together by the spring G, the guides I, the spudder which is 45 placed between them, and the catch for holding the lath, substantially as specified.

In testimony whereof we affix our signatures in presence of two witnesses.
